UNITED STATES PATENT OFFICE.

EPHRIAM J. SCOTT, OF EAST PROVIDENCE, RHODE ISLAND.

DESIGN FOR A GAME-BOARD.

56,200.

Specification for Design.

Patented Aug. 24, 1920.

Application filed September 22, 1919. Serial No. 325,560. Term of patent 3½ years.

To all whom it may concern:

Be it known that I, EPHRIAM J. Scott, a citizen of the United States, residing at the town of East Providence, county of Providence, State of Rhode Island, have invented a new, original, and ornamental Design for a Game-Board, of which the following is a specification, reference being had to the accompanying drawing, forming part thereof.

The figure is a perspective view of a game board, illustrating my new design.

I claim:

The ornamental design for a game board, as shown.

EPHRIAM J. SCOTT.
